UNITED STATES PATENT OFFICE.

EARL HOUSTIN REYNOLDS, OF PROPHETSTOWN, ILLINOIS.

CHECK-ROW CORN-PLANTER.

SPECIFICATION forming part of Letters Patent No. 334,470, dated January 19, 1886.

Application filed July 27, 1885. Serial No. 172,781. (No model.)

To all whom it may concern:

Be it known that I, EARL H. REYNOLDS, a citizen of the United States, residing at Prophetstown, in the county of Whiteside and State of Illinois, have invented a new and useful Improvement in Check-Row Corn-Planters, of which the following is a specification, reference being had to the accompanying drawings.

10 My invention relates to an improvement in check-row corn-planters; and it consists in the peculiar construction and combination of devices that will be more fully set forth hereinafter, and particularly pointed out in the 15 claims.

This invention is adapted particularly to operate in connection with the corn-planter for which I obtained Letters Patent of the United States, February 19, 1884, No. 293,672.

20 In the accompanying drawings, Figure 1 is a top plan view of a corn-planter with my improved devices attached thereto. Fig. 2 is a side elevation of the same. Fig. 3 is a detailed view of the reel and its attachments.

25 A represents the seed-boxes of an ordinary planter, and B is the seed-slide.

D represents an axle in rear of the seed-boxes, having driving and supporting wheels D', and projecting squared spindles D² beyond 30 the wheels, as shown.

C designates brackets, that are secured upon the inner sides of the seed-boxes. These brackets carry a cross-bar, F, the ends of which have vertically-projecting spindles f, 35 upon which are mounted the brackets G, which are each formed of two plates, between which, at their outer corners, are journaled horizontal pulleys H, and at their inner corners horizontal pulleys I. Studs K also project above the bar F and enter segmental slots g in the lower plates of brackets G, thereby limiting the movement of the latter on their spindles f.

To the center of the bar F, on the upper 45 side thereof, is journaled a guide-disk, M, which consists of a casting comprising a pair of horizontal parallel cruciform plates, the front and rear arms of which are integrally connected by the loops or bows N. The upper 50 and lower plates, O and P, are provided, respectively, with upward and downward pro-

jecting spindles Q R, which are journaled, respectively, in a bracket, L, and in the cross-bar F. The side arms, S, of the cruciform plates are connected with the front and rear 55 arms, T, by means of inclined braces U, forming tracks, upon which the tappets of the check-wire may slide, as will be hereinafter more fully described. Metallic braces or stiffeners V are also provided that connect the 60 ends of the arms S with the loops or bows M. The upper spindle, Q, of the guide-disk is provided with a crank, W, connected by a pitman, X, and rock-shaft Y, having an arm, Z, with the seed-slide. Secured to the outer 65 sides of the driving-wheels, and revolving therewith, are spur-wheels a.

b represents a bracket that is secured on one of the squared spindles of the axle, and carries a shaft, e, to the inner end of which is fixed 70 a spur-wheel, d, that meshes with wheel a.

Extending from the outer end of the shaft e, at a slight angle thereto, is a rod, e, on which is mounted a reel, h. Friction-plates l are also on said rod on opposite sides of the 75 reel, and are caused to bind against said reel with greater or less force by the coiled spring m, which is wrapped around the rod e, and the tension of which may be strengthened or reduced by a clamp-nut, n, that 80 screws on the rod. The reel is thus caused to rotate with the rod by frictional contact with the plates. A check-wire, p, which is provided with the usual buttons or tappets, r, is attached at one end to the reel, and from 85 thence passes over the front pulley, H, at one end of the machine, between the guide-pulleys I, between the plates forming the guide-disks, between guide-pulleys I, and over the pulley H at the other end of the machine, its 90 free end being anchored across the field from the machine. As the machine is drawn along in a line with the wire, the tappets thereof will work the seed-slide at regular intervals by means of the mechanism hereinbefore fully 95 described, and as will be very readily understood, and the reel being rotated by the gear-wheels a and d will wind up the wire as the machine progresses. The tendency of the reel is to wind the wire faster than the rate of 100 travel of the machine, thus keeping the wire taut in advance of the machine. If the reel

was rigidly secured to the rod *c*, this would result in breaking the wire, owing to the strain thereon; but this is avoided by having the reel loose on the rod, and caused to rotate therewith by being clamped between the friction-plates, which allow the reel to slip on the rod when the strain on the wire endangers its safety. When the end of the row is reached, the machine is turned around and drawn in a contrary direction, when the wire will be unwound by the reel as its tappets operate the planting mechanism, as will be readily understood.

I am aware that it is broadly old to employ a spring-actuated friction disk and nut to hold the reel tight on the shaft.

I am also aware that it is old to attach the reel on the outside of the carrying-wheels, and employ suitable gearing for actuating the reel-shaft from the axle of the carrying-wheels.

Having thus described my invention, I claim—

1. In a check-row corn-planter, the combination, with the axle provided with the projecting spindles *D* and spur-wheels *a*, located on the spindles so as to rotate with the supporting-wheels, of the bracket *b*, secured on the spindles outside of the spur-wheels *a*, the transverse shaft *c*, journaled in the bracket, the

pinion *d* on the inner end of the shaft, meshing with the spur-wheels *a*, the rod *e*, extending from the outer end of shaft *c* and having the threaded outer end, the reel *h*, loose on the rod *e*, the loose friction-plates *l*, pressing against opposite sides of the reel, the spring *m*, bearing against one of the friction-plates, and the nut located on the threaded outer end of the rod *e*, for pressing against the spring, as and for the purpose set forth.

2. The combination, with a check-row corn-planter having its axle provided with a spur-wheel, *a*, of a suitably-journalized shaft having a pinion, *d*, at one end meshing with the spur-wheel, the reel loose on the shaft, loose friction-plates mounted on the shaft on each side of the reel, a spring on the outer end of the shaft pressing against one of the plates, and a nut working over the threaded end of the shaft against the spring to compress the latter, as set forth.

In testimony that I claim the foregoing as my own I have hereto affixed my signature in presence of two witnesses.

EARL HOUSTIN REYNOLDS.
